CLAIM

The ornamental design for a proppant storage container, as shown and described.

DESCRIPTION

FIG. 1 is an upper perspective view of the proppant storage container;

FIG. 2 is a lower perspective view of the proppant container shown in FIG. 1;

FIG. 3 is a front elevation view of the proppant storage container shown in FIG. 1;

FIG. 4 is a rear elevation view of the proppant storage container shown in FIG. 1;

FIG. 5 is a left-side elevation view of the proppant storage container shown in FIG. 1;

FIG. 6 is a right-side elevation view of the proppant storage container shown in FIG. 1;

FIG. 7 is a top plan view of the proppant storage container shown in FIG. 1; and,

FIG. 8 is a bottom plan view of the proppant storage container shown in FIG. 1.

The broken lines shown in the figures represent portions of the proppant storage container that form no part of the claimed design.

1 Claim, 8 Drawing Sheets
